UNITED STATES PATENT OFFICE.

J. L. CROWLEY AND L. J. JOHNSON, OF MARION, IOWA.

IMPROVEMENT IN SUGAR-EVAPORATORS.

Specification forming part of Letters Patent No. 36,076, dated August 5, 1862.

To all whom it may concern:

Be it known that we, J. L. CROWLEY and L. J. JOHNSON, of Marion, Linn county, and State of Iowa, have invented certain new and useful Improvements in Apparatus for Evaporating Sacharine Juices; and we hereby declare that the following is a true and exact description of the same, reference being had to the accompanying drawings, and to the letters of reference marked thereon.

In the annexed drawings, Figure 1 represents a longitudinal section of the furnace with the evaporating apparatus in position, and Fig. 2 exhibits a plan view of the same.

B' and B² represent the two hot-air chambers, extending lengthwise over the furnace A, the top of B² being a little lower than the bottom of B'.

C is an evaporator constructed with a partition in line with the furnace and dividing C into two equal compartments, each being equal in length and width with B², over which it is placed. The sliding door or gate e is adjusted to the center of the partition for the purpose of transferring the sirup from one compartment to the other when necessary.

D is a purifier made a little larger than hot-air chamber B', and resting immediately on it. At the end of D are two conduits, p p, to convey the prepared juice into the evaporator C.

E is a movable frame, fitted accurately in purifier D, and is furnished with the arms e e to facilitate its removal when desired. The sides and ends of frame E may be made either of sheet metal or of any strainer material, such as is represented by G or F. We do not confine ourselves to one frame, as several may be used, each with its appropriate strainers. Half-way of the depth of the frame E the perforated metal plate is placed, and represented by G, and resting on steps inside E. Beneath G, and near the bottom of E, is the strainer F, the edges of E being chamfered to receive it. This strainer can be easily removed and made to serve the purpose of a skimmer. The gallows consists of the two supporters u u, fastened to the sides of the furnace A and united by the cross-tie H, which passes diagonally over E. To this cross-tie a pulley may be attached for the

easy removal of E from its position in the purifier D.

I I I are slides or dampers between the furnace A and hot-air chambers B' and B², by which the action of the fire on the purifier D and the evaporator C can be increased and diminished at pleasure. Any number of these dampers may be used.

K constitutes the angular flue situated between the two hot-air chambers.

J^o J, as shown in Fig. 3, are partitions in the hot-air chambers, and serve to guide the heated air in its passage through the hot-air chambers, and make a continuous flue from one side of K, the point of its admission, then along the partition J^o in B', returning on the opposite side of J^o to flue K, and to the chimney M.

L represents a cross-plate covering the rear of the furnace A, having two openings, l l, marked with dotted lines in Fig. 2, one opening communicating with the furnace and the other with hot-air chamber B².

M is a movable chimney made to slide in L through the grooves m m, and is adjustable either to the hot-air chamber or to the furnace.

The two Figs. 8 8 represent two views of nests of strainers, N being a vertical section and S a plan view. This nest consists of a series of strainers arranged in the form of steps, beginning with strainer No. 1, coarse, and ending with No. 3, fine, and can be adjusted beneath the conduit of either compartment of C to draw off and strain the sirup. The shank at the end of N enters the sheath under C, and may be supported at the opposite end by legs.

R is the door under the chimney hinged at the bottom and intended for the removal of ashes. P' is the door at the opposite end of the furnace for the admission of fuel.

Q Q Q Q are elbows, the upper or horizontal part being in line with the top of air-chamber B², and securely fastened to it and the lower part attached to the legs of furnace. Upon these the hot-air chamber C is made to slide, so that either of its compartments may in turn be brought over the furnace A.

Having thus accurately described our invention, what we claim, and desire to secure by Letters Patent, is—

1. The movable frame E, in combination with the adjustable strainer and skimmer F, the metallic skimmer G, and the frame H, operated in the manner and for the purpose set forth.

2. The angular tube K, in combination with the opening l l and the adjustable chimney M, for the purpose herein specified.

3. The nest of strainers N, for the purpose herein set forth.

J. L. CROWLEY.
L. J. JOHNSON.
